Application July 11, 1946, Serial No. 682,974

23 Claims. (Cl. 60—97)

1

This invention relates to hydraulic apparatus and more specifically to hydraulically actuated presses.

An object of this invention is to provide a hydraulic press with a work holder which is moved intermittently to successively register work stations thereon with the ram of the press.

Another object of this invention is to provide a hydraulic press with a work holder or table which is actuated by hydraulic pressure and is synchronized with the operation of the press ram so that the movement of the table will occur between successive operations of the press ram and not simultaneously therewith.

Another object of the invention is to provide a hydraulic press with an index table, the press having a control mechanism for governing the operation of the press ram and synchronizing the operations of the ram and the index table, the latter being driven by a fluid motor having a hydraulic circuit including flow control means for regulating the rate of operation of the fluid motor and valve means actuated by the fluid motor for directing a charge of fluid under pressure to the control mechanism to initiate the operation of the pressing ram when the index table or its driving mechanism is at a predetermined stage of operation.

A further object is to provide a press of the character mentioned in the preceding paragraph with means for adjusting the flow control means whereby the rate of operation of the fluid motor may be varied, the flow control having a flow throttling spool responsive to a fluid pressure drop caused by an orifice disposed in a fluid line, the adjusting means serving to change the size of the orifice.

A still further object of the invention is to provide a fluid pressure operated press and index table having a control mechanism which is operative to direct fluid to either the press ram or the motor for driving the table whereby one or the other of these mechanisms is operated and to provide the portion of the circuit including the table driving motor with means responsive to the operation of the motor to change the rate of operation thereof at certain stages in a cycle of operation of the table, the mechanism thus providing for slow motor operation during table travel, rapid operation of the motor during a portion of the stationary or rest period of the table and a complete stoppage of the table driving motor during another portion of the rest period of the table while the press ram is in operation.

Another object is to provide a hydraulically op-

2

erated press and index table in which the table is intermittently operated by a Geneva gearing having a star wheel and driver and providing the press and table with a circuit including control mechanism operative to direct full pump volume to the press ram during the cycle of operation thereof, then full pump volume to the indexing table during its indexing period, the control mechanism also serving to stop the Geneva driver at a point in its cycle of movement spaced substantially midway between the termination and commencement of successive indexing periods in order to securely lock the table in indexed position which locked condition will be maintained for the full period required by the ram in its pressing operation, thus the table will be securely retained in position during each pressing stroke whether the time required is prolonged or abbreviated.

20 An object also is to provide the control mechanism of the press and index table mentioned in the preceding paragraph with means for causing full speed operation of the table driving motor during the movement of the Geneva driver from the termination of an indexing period to the point of stoppage and from the latter to the start of the next succeeding indexing period, this full speed operation of the driving motor serving to reduce the time elapsing between the termination of table movement and the initiation of a ram operation.

25 An object of the invention also is to provide a hydraulic press with an index table and control mechanism therefor which will cause the press ram to operate each time the table indexes or, as an alternative, to remain inoperative for one or more indexing periods.

30 An object also is to provide a hydraulic press with an index table and control mechanism operated in part by the index table to cause the ram to remain at rest when one or more work stations are registered therewith, the table continuing the indexing operations until a work station is registered with the ram at which station it is desired to perform a pressing operation. The press having such mode of operation is useful where an insufficient number of die sets are available to supply all work stations or where it is desirable to interrupt the pressing operation on a particular die set, for example, in the event breakage should occur during an operating period.

35 Another object is to provide a hydraulic press with an index table and means operative during the rotation of the table to eject articles from the 55 die pieces carried by the table as the die pieces

move away from or out of registration with the ram after an operation is performed on the materials carried by the die pieces.

Further objects and advantages of the present invention will be apparent from the following description, reference being had to the accompanying drawings wherein a preferred form of embodiment of the invention is clearly shown.

In the drawings:

Fig. 1 is a side elevational view of a hydraulic press with an index table formed in accordance with the present invention.

Fig. 2 is a front elevational view of the press shown in Fig. 1.

Fig. 3 is a detail vertical sectional view taken through the index table on the plane indicated by the line III—III of Fig. 2.

Fig. 4 is a fragmentary horizontal sectional view taken through the table on the plane indicated by the line IV—IV of Fig. 3.

Fig. 5 is a detail vertical sectional view taken through the control valve mechanism of the index table on the plane indicated by the line V—V of Fig. 2.

Fig. 6 is a detail vertical sectional view taken through the index table control valve on the plane indicated by the line VI—VI of Fig. 1.

Fig. 7 is a fragmentary transverse sectional view taken through the valve on the plane indicated by the line VII—VII of Fig. 6.

Fig. 8 is a diagrammatic view of the hydraulic circuit employed in operating the press and index table shown in Fig. 1.

Fig. 9 is a developed view of a cam employed to operate the index table control valve.

Fig. 10 is a detail horizontal sectional view taken through a three-way valve actuated by the index table to cause the press ram to skip one or more stations.

Fig. 11 is a fragmentary vertical sectional view taken through the upper portion of the index table to show the mechanism for ejecting articles from die pieces carried by the table.

Fig. 12 is a diagrammatic view of a modified hydraulic circuit employed when the hydraulic index table is used without the control mechanism 27 and the ram 31.

Referring more particularly to the drawings, the press illustrated in Fig. 1 is designated generally by the reference numeral 20. This press includes integral base, upright, and head sections 21, 22, and 23 respectively, these portions of the press constituting a generally C-shaped frame housing a fluid reservoir or tank T, a motor-driven pump 24, a relief valve 25, a power cylinder 26, and automatic control valve mechanism indicated generally by the numeral 27; the power cylinder and control valve mechanism being located within the head section 23 of the press 20.

The power cylinder 26 includes a cylindrical body having a piston chamber 28 in which a piston 30 is disposed for sliding movement. This piston is connected with a ram 31 which projects through the bottom wall of the cylinder through a packing gland 32 into the space between the over-hanging head and the base section of the press frame. When the piston 30 is reciprocated in the power cylinder, similar movement will be imparted to the ram 31 to perform useful work. The reciprocations of the piston 30 are controlled by the valve mechanism 27 which may be of either type set forth in my co-pending applications Serial Nos. 594,963 and 600,736, filed May 21, 1945 and June 21, 1945,

respectively, the particular control mechanism selected for illustration conforming to that shown in application Serial No. 600,736. To assist in operating the valve mechanism, the ram 31 is provided with a rearwardly directed arm 33 which slidably engages a shipper rod 34 depending from one of the movable elements 35 of the control valve mechanism. Motion is imparted to the shipper rod by the arm 33 as the piston and ram approach the limits of their travel through the engagement of the arm with spaced collars 36 and 37 secured to the shipper rod 34. Since the valve mechanism is similar to that defined in the co-pending application Serial No. 600,736 it will therefore only be generally described herein, reference being had to the co-pending application for a more detailed description.

In general, valve mechanism 27 includes a body 38 having a pair of piston chambers 40 and 41 formed therein, the former slidably receiving valve element 35, which is of sleeve-like formation, and the latter slidably receiving a valve spool 42. The body 38 includes a plurality of annular grooves 43 to 48 inclusive, spaced longitudinally of the chamber 40 and the sleeve-like valve element 35 is provided with longitudinally spaced ports 53 to 60 inclusive, which, in various longitudinal positions of the element 35, register with certain of the grooves 43 to 48. A piston-like shuttle valve 61 is disposed for sliding movement within the sleeve element 35 to control communication between certain of the ports in the valve element, the shuttle valve having a reduced portion to provide in cooperation with the sleeve 35 a passage within the same. Normally the shuttle valve is held in a lower-most position by a coil spring 62 disposed between the upper end of the sleeve and an interior shoulder formed in the shuttle valve.

The sleeve-like element 35 is normally urged toward a centered position in the bore or chamber 40 also by a coil spring 63 disposed between a pair of spring abutments 64 and 65 at the lower end of the chamber 40. When the sleeve and shuttle valves are disposed in this relation, the relieved portion of the shuttle valve connects ports 56 and 58 which are, at this time, in communication with annular grooves 43 and 46 formed in the body 38. Groove 43 is at all times connected with a source of fluid pressure comprising the tank T, pump 24, and relief valve 25 through a conductor 66. Groove 46 is connected with the lower end of the power cylinder 26 by a conductor 67. When the valve parts are so disposed, fluid is supplied to the lower end of the power cylinder and exerts an upward force on the piston 30. To permit upward movement of the piston 30, fluid in the upper end of the power cylinder is discharged through conduit 68 to annular groove 45, through ports 59, the interior of sleeve 35 and, through ports 60 to groove 48 which is connected by passage 70 with tank T. As the piston 30 and the ram 31 secured thereto approach the upper limit of their travel, arm 33 engages collar 36 and moves the valve element 35 in an upward direction to interrupt communication between ports 56 and the annular groove 46. When this communication is fully interrupted, further movement of the ram in an upward direction will be precluded. However, before such movement is completely interrupted, ports 57 in the valve element 35 are registered with annular groove 44 which groove is connected by passage 71 with chamber 41. Fluid conductor 72 extends

from the chamber 41 to driving apparatus for an index table designated generally by the numeral 73 supported on the base section 21 of the press frame, the fluid being supplied to the conductors 71 and 72 when the ram 31 is in an elevated idle position.

Referring particularly to Figs. 3 and 4, it will be observed that the index table 73 includes a base casting 74 which is bolted or otherwise secured to the press frame. This base casting is hollow and is formed with a central recess 75 for the reception of a bearing sleeve 76 which in turn receives the lower end of a hub 77 forming a part of the star wheel 78 of a Geneva drive 80. The upper end of the hub 77 is received in a bearing 81 which is supported in a cover casting 82 secured to the open upper end of the base 74. Antifriction ball-bearing assembly 83 is also disposed around the upper end of the hub 77, the bearing 83 including upper and lower races 84 and 85 which are spaced by ball bearings 86, the assembly being clamped in place by a retaining ring 87 bolted or otherwise secured to the cover 82. The upper end of the hub 77 also receives a disk-like plate 88 which forms the work-receiving surface of the index table, this plate 88 being fastened to the hub by screws and dowls 90 and 91, respectively. The underside of plate 88 is disposed in sliding engagement with a ring-like finished pad 92 at the periphery of the cover 82. To effect rotary movement of the plate 88, the base and cover sections 74 and 82 are provided with a second set of registering recesses in which a second hub 93 is journaled, this hub forming a part of the driver 94 of the Geneva mechanism. The hub 93 includes a pair of spaced laterally projecting arms 94 between which a roller 95 is mounted for rotation. As is customary in Geneva drives, the star wheel 78 has a plurality of alternately disposed arcuate recesses and radial slots 96 and 97, respectively. The journals for the hub 93 are so arranged that the hub will fit in the arcuate recesses 96 and hold the star wheel stationary while the hub rotates through the portion of its travel during which the table is idle. As the hub 93 rotates, the roller 95 will enter a radial slot 97 and transmit rotary movement to the star wheel which will in turn transmit similar movement to the disk 88, the latter being intermittently driven as is usual with Geneva gears. When the driver section 94 of the Geneva gear is disposed in the position shown in Fig. 4, the star wheel will be securely locked against rotary movement. One of the features of the present invention is to discontinue the operation of the table driving mechanism when the ram 31 is performing a pressing operation. During the stationary period of the index table, the driver is maintained in the position shown in Fig. 4 in which the most securely locked condition of the table obtains. The manner in which the driver is held in this position will be set forth hereinafter. To effect the operation of the Geneva driver, the hub 93 is provided with a gear 98 which meshes with a pinion 100 arranged on the shaft 101 of a fluid motor 102. This motor is supplied with fluid to effect the rotation of the table when the ram is idle between successive pressing operations, the fluid being conducted to the motor through the conductor 72 which, as previously stated, communicates with the bore 41 in the body 38.

To govern the operation of the fluid motor, valve mechanism indicated generally by the numeral 103, has been provided. This valve mech-

anism is contained within a valve body 104 supported by the fluid motor housing 105 which is in turn suspended from the under side of the index table base 74. The valve body 104 has a pair of parallel piston chambers 106 and 107 formed therein, the body having annular grooves spaced longitudinally of the chambers 106 and 107. Chambers 106 and 107 have valve spools 108 and 110 respectively, slidably disposed therein. The spools 108 and 110 are employed for governing the rate of operation of the fluid motor 102 and the application of fluid under pressure to a part of the control valve mechanism 27 to effect the initiation of a cycle of operation of the ram 31 upon the completion of an indexing movement of the table.

Attention is directed to the flow diagram in Fig. 8, this diagram illustrates the connection of the conduit 72 with an annular groove 111 forming a part of chamber 106 and an annular groove 112 forming a part of chamber 107. Normally the spool 108 is held in a centered position by coil springs 113 and 114 in which position groove 111 openly communicates with groove 114A also forming a part of chamber 106. Groove 114A is connected by conduit 115 with the inlet of the fluid motor 102. The outlet of this motor is connected by line 116 with tank T, the line containing a fixed orifice 116A and a variable orifice 117. A branch line 118 is connected with line 116 between the orifices 116A and 117 and extends to a groove 120 forming a part of the chamber 107. The body 104 has another groove 121 adjacent the groove 120, the former being connected by a branch line 122 with line 116 between orifice 117 and tank T. In one position of the spool 110 grooves 120 and 121 are connected so that fluid may flow from the fluid motor 102 directly to tank T without flowing through the orifice 117. When this condition obtains, full volume of the pump 24 will be supplied to the fluid motor to cause relatively rapid movement of the Geneva driver 94. After this mechanism and gear 98 has rotated through a predetermined angle, motion 45 is imparted to the spool 110 by a pushrod 123 which has a roller 124 journaled in its upper end, the roller being disposed for engagement with a cam track 125 provided on the under surface of the gear 98. In the diagrammatic Figures 8 and 12 push rod 123 is shown as one continuous piece while actually it is composed of two pieces as shown in Figs. 3, 5, and 6, for ease in construction and assembly. Cam track 125 is so formed that the spool 110 will be held in position to connect 50 grooves 120 and 121 during a certain portion of a revolution of a gear 98 then moved to and held in a second position in which such communication is interrupted during another portion of the revolution of gear 98. Spool 110 will be disposed 55 in the second position, mentioned above, when the roller 124 is engaged with the thinnest portion of the cam track 25 designated as two sections 105° and 35° of revolution in length in the developed view Fig. 9. Actually these two sections are connected and form a portion of the cam track 140° of revolution in length. At the time grooves 120 and 121 are not in communication fluid discharged from the fluid motor 102 must pass through the orifice 117 which creates 60 in the second position, mentioned above, when the roller 124 is engaged with the thinnest portion of the cam track 25 designated as two sections 105° and 35° of revolution in length in the developed view Fig. 9. Actually these two sections are connected and form a portion of the cam track 140° of revolution in length. At the time grooves 120 and 121 are not in communication fluid discharged from the fluid motor 102 must pass through the orifice 117 which creates 65 a pressure drop on opposite sides of this orifice. The higher pressure is transmitted from line 116 through line 118 and annular groove 120 to a line 126 which connects groove 120 and the upper end of chamber 106. Also at this time the lower 70 end of this chamber is connected by line 127,

groove 50 in body 38 of the valve mechanism 27, line 128, groove 47, ports 53, and the interior of the shuttle valve with groove 48 which in turn is connected by line 70 with the tank T. The pressure differential exerted on opposite sides of the orifice 117 will thus be transmitted to opposite ends of the spool 108 causing this member to move downwardly in opposition to the spring 114 to permit a tapered section 130 on the spool to move toward a groove 131 formed adjacent the groove 114A, the degree of movement of the spool 108 depending upon the pressure differential. Due to the tapered portion 130, a variable degree of metered communication will be established between the grooves 114A and 131, the latter of which is connected by line 132 with tank T. When communication is thus established between grooves 114A and 131, a variable quantity of fluid flowing through line 72 will be bypassed directly to tank T to reduce the quantity of fluid flowing to the fluid motor 102, thus decreasing the rate of operation thereof as well as that of the index table. This flow control is utilized during the period of engagement of roller 95 in the slots 97 of the Geneva star wheel and consequently during the movement of the table between pressing stations.

When the roller 95 passes out of any particular groove 97 the cam track 125 will cause the movement of the spool 110 to a position to again establish communication between grooves 120 and 121. At this time roller 124 will be riding on the intermediate level of the cam track designated in the developed view Fig. 9, as 105° of revolution in length. When communication is re-established between grooves 120 and 121 the pressure differential will be dissipated, permitting spool 108 to again resume its centered position. When this condition obtains, full pump volume will again be directed to the fluid motor 102 to resume the rapid rate of operation of the motor, the driver 94 and gear 98. Immediately prior to the time that the Geneva driver reaches the position shown in Fig. 4, that is, the position in which the index table is fully locked, a projection 133 on cam track 125 will cause the spool 110 to be depressed until communication is established between groove 112 and another groove 134, formed in the body 104, adjacent the groove 112; this groove 134 is connected with line 127 by a branch 135. When the spool 110 is depressed sufficiently to establish this communication, full pump volume will be directed through line 72, grooves 112 and 134, line 127, groove 50, line 128, groove 47, and ports 53 to the interior of sleeve 35 beneath shuttle valve 61. Due to the restriction 61A in the central passage through this shuttle valve, the fluid pressure will cause the shuttle valve to move upwardly in opposition to spring 62, to a position in which ports 58 and 59 will be connected to direct fluid under pressure from the pump to the upper end of the power cylinder 26. A cycle of movement of the ram will thus be initiated.

When the shuttle valve 61 is in a raised position, a chamber 136 formed in the lower end thereof will be connected with the groove 46 by ports 56 and fluid flowing from the lower end of the power cylinder through chamber 136 to exhaust will be restricted by the reduced orifice 61A formed in the shuttle valve to create a back pressure which will be transmitted to the underside of the shuttle valve to hold the same in the elevated position. This back pressure will be transmitted also through line 128, groove 58 and lines 127 and 135 to the groove 134 where it will

act on the upper end of the spool 110 to hold this element depressed and maintain communication between grooves 112 and 134. Although the raising of the shuttle valve interrupts the flow of fluid to motor 102 there is sufficient overtravel or coasting of this device and the Geneva driver to permit the projection 133 to move beyond roller 124. This overtravel is limited, however, by the restricted orifice 116A, which orifice also supplies sufficient resistance to insure the flow of fluid from line 72 to 127 through grooves 112 and 134 when spool 110 is depressed. After the projection 133 moves beyond roller 124, the push rod 123 is returned to elevated position by the back pressure in groove 134, spool 110 and push rod 123 being formed of separate pieces to permit this action. The back pressure will also be transmitted by line 127 to the lower end of chamber 106 and applied to the under side of spool 108 to move the same to a position in which a land 137 thereon will obstruct communication between grooves 111 and 114A. At this time relieved portions 138 formed on the spool 108 will establish communication between grooves 114A and 131 and the inlet to the fluid motor will thus be connected directly to tank T through line 115, grooves 114A and 131 and line 132. With spool 110 also depressed so that communication is established between grooves 120 and 121, the outlet of the fluid motor will likewise be connected with tank T and the fluid motor will therefore remain idle, this condition will be maintained during the continuation of the back pressure which will be the full time the ram is moving downward. Since no driving force is transmitted to the Geneva driver, the star wheel and table will be held in locked position. At this time a work-receiving station on the index table will be in registration with the ram 31.

After the cycle of operation of the ram has been initiated, ram movement will be continued until the ram engages an obstruction offering sufficient resistance to prevent further movement, or the arm 33 engages collar 37 and moves sleeve 35 to a lowered position wherein the groove 48 will be connected with groove 46 thus discontinuing fluid flow to the top of cylinder 26. The ram will then stop moving and the back pressure will be instantly dissipated permitting shuttle valve 61 to return, under the influence of spring 62, to a lowered position. When the ram is stopped by engagement with an obstruction or otherwise, the back pressure will be dissipated through the interior of the shuttle valve and spring 62 will cause the shuttle valve to return to its lowered position. In either event, the return of the shuttle valve will cause a reversal of fluid flow to the ends of a power cylinder and piston 30 will be caused to make a return stroke. This movement causes the elevation of ram 31. As the ram approaches the upper limit of its travel, arm 33 will engage collar 36 and move the shipper rod 34 and sleeve 35 upwardly until communication between the interior of the sleeve and groove 46 is interrupted. Ram movement will then be discontinued as previously described. The upward movement of the sleeve 35 effects registration of ports 57 and groove 44 wherein fluid under pressure supplied to the control valve mechanism 27 will again be directed through lines 71 and 72 to the table operating mechanism, the cycle of operation will then be repeated. It is important to note at this point that valve spool 42 must be disposed in a lowered position where- 70 75 in the land at the upper end thereof prevents

fluid admitted through line 71 from flowing to groove 51 and being exhausted to tank to have the cycle of operation repeat automatically.

The rate of movement of the index table may be varied by changing the setting of the variable orifice 117. One convenient form of orifice has been disclosed in Figs. 6 and 7; this form of orifice includes a tube 140 disposed for rotation in the body 104 and provided with a narrow, transverse slot 141 which may be gradually uncovered through turning movement of the tube. As the tube is turned and more or less of the slot uncovered, the quantity of fluid permitted to flow through the slot 141 will be varied to change the pressure differential existing between the up and down stream sides of the orifice. If the pressure drop is large, more fluid will be permitted to bypass the fluid motor and slower table operation will result. The outer end of the tube 140 is provided with a control knob 142 to effect easy adjustment of the orifice.

In some instances it is desirable to have the ram 31 remain idle when one or more of the stations on the table are registered therewith for example, if the table should be provided with die pieces of various types and it becomes desirable to refrain from using one of the types, the ram may be forced to remain idle when this particular die piece is registered therewith. To effect this operation, the table is provided with a 3-way valve designated generally by the numeral 143. This valve includes a body 144 which is supported by the cover plate 82 adjacent the edge of the disk 88. The body 144 is formed with an internal chamber 145 for the slideable reception of a spool 146, this spool being normally held in an outward position by a coil spring 147. When in this position the valve is closed and inoperative. Operation of the valve is effected by cam element 148 removably secured to the edge of the disk 88 which, as the disk revolves, engages a roller 150 journaled in the outer end of the spool 146; this cam moves the spool inwardly to the position shown in Fig. 10, wherein a groove 151 in the spool establishes communication between a pair of grooves 152 and 153 in the body 144, groove 152 being connected with line 127 by conduit 154, and groove 153 being connected with tank T. After cam 148 has moved spool 146 to open the valve 143, cam 125 depresses spool 110 to supply line 127 with fluid under pressure. Under ordinary conditions the fluid thus supplied to the line 127 would serve to elevate the shuttle valve 61 to initiate a cycle of movement of the ram 31. When the valve 143 is open, however, the fluid supplied to the line 127 will be conducted directly to tank T. Since no fluid is supplied to the under side of the shuttle valve at this time, the ram 31 will remain idle and the index table will be moved to the next station.

When the valve 143 is open, the fluid supplied to line 127 will not hold spool 110 depressed since the fluid is under no pressure. Due to the over travel of the fluid motor and the drive of the Geneva gearing, and the lack of pressure in groove 134, spool 110 will immediately return to its elevated position in which fluid supplied through line 72 will be directed to the fluid motor 102 and its operation will be continued without substantial interruption. If the disk 88 is provided with a cam 148 for the next station, the ram 31 will remain idle at this station also. If no cam 148 is provided, the fluid supplied to the line 127, by the depression of the spool 110, will initiate a cycle of movement of the ram 31 and a

pressing operation will be performed. The cam 148 has a pair of slotted pins 156 projecting therefrom which are received in openings 157 formed in the edge of the disk 88, the friction of these pins in the openings retaining the cam in position. If it is desired to have the ram perform a pressing operation at the station corresponding to any particular cam location it is merely necessary to manually remove the cam 148 to permit normal operation of the control circuit for initiating ram operation.

In some instances it is desirable to eject formed articles from die sets after a pressing operation has been performed. Fig. 11 illustrates one method of securing such ejecting operation. In the form of the invention shown in Fig. 11, the cover plate 82 has a cam track 158 secured to its upper surface; this cam track 158 is circularly formed and is disposed in registration with the work-receiving stations on the disk 88, the disk being provided at these stations with openings 160, these openings slidably receive pins 161 which are normally urged downwardly by coil springs 162, arranged in the die sets 163 secured to the upper surface of the disk 88 at the work-receiving stations. Fig. 11 diagrammatically illustrates the die sets 163; it should be obvious that the die sets actually employed may vary considerably from those indicated, the diagrammatic illustration being employed merely to facilitate the explanation. The springs 162 engage an annular flange on the pins 161 and an abutting cap piece 164 which forms a part of the die set 163. This arrangement permits the spring to urge the pins downwardly so that the article undergoing pressing will remain in the die set. After passing the pressing station, the lower ends of the pins 161 will engage an elevation on the cam track 158 which will cause the pins 161 to move upwardly in opposition to the springs 162. This upward movement of the pins will eject the work from the die sets and the work may be either manually or otherwise removed after ejection. Continued rotation of the table moves the pins over a declining section of the cam track and the springs 162 will cause the lowering of the pins 161.

Fig. 12 shows a flow diagram for a hydraulic index table utilized alone. This circuit includes the reservoir T, a pump 165, a relief valve 166 and a line 167 connecting these elements with the inlet of the control mechanism 103 for the index table. The line 167 corresponds to the line 72 in the circuit shown in Fig. 8. Line 168, in Fig. 12, which corresponds to line 127 in Fig. 8, extends to the inlet of a normally closed solenoid or otherwise actuated "on and off" valve 170, the outlet of this valve being connected to tank T.

By momentarily opening valve 170 the table will be indexed one station; this indexing operation will only be repeated when valve 170 is again opened.

The circuit in the control mechanism is identical with the corresponding portion of the circuit shown in Fig. 8.

Fig. 12 illustrates the parts of the control mechanism in the positions occupied when the circuit is in actual operation. At this time, fluid pressure supplied through line 167 flows into groove 112, past the upper end of spool 110 to groove 134 where it exerts a force on the upper end of spool 110 to hold it in a depressed position. This pressure also is transmitted through lines 135 and 168 to the lower end of bore 106 where it exerts force on the bottom of spool 108 to move the same upwardly against the action

of spring 113, to a position in which land 137 on the spool prevents the flow of fluid from groove 111 to groove 114, the latter being connected to groove 131 and tank T at this time. Since no fluid is supplied to the motor 102 and the inlet is connected with the exhaust the motor will be idle.

As in the circuit shown in Fig. 8, spool 110, when depressed, connects grooves 120 and 121 so that the outlet of the fluid motor 102 is also connected directly to tank T.

Pressure exists in line 168 because of the normally closed valve 170 and as long as this valve remains closed when the fluid pressure source is active the fluid motor 102 will remain idle. When it is desired to cause the table to index, the valve 170 is opened to dissipate the pressure in line 168. Pressure will also be dissipated in chamber 134 and in the lower end of bore 106. Spool 110 will then return into engagement with pusher 123 and spool 108 will be centered in which position fluid from line 167 may flow to the fluid motor 102. Rotation of the motor will cause the table to index to the next station. If valve 170 has been permitted to close, the depression of spool 110 by cam extension 133 will again supply fluid pressure to groove 134 and the lower end of bore 106 which pressure will retain spool 110 depressed and raise spool 108 whereby fluid flow to the motor 102 will be interrupted as above described.

The table may also be caused to skip one or more stations when employed alone in the same manner as when used in combination with the pressing ram. To effect this operation the 3-way valve 143 is employed as before with the inlet thereof connected with line 168. The edge of the disk-like table is provided with a removable cam or cams which hold the valve 143 open when the spool 110 is depressed by cam projection 133. When valve 143 is so positioned pressure will not build up in line 168, spool 110 will not be held depressed and spool 108 will not be moved up to interrupt fluid flow to motor 102. The table will, therefore, index or move to the next station.

A branch line 171 extends from the line 168 in advance of valve 170, to tank, this branch line containing an orifice 172 which permits some fluid to flow to tank but insufficient fluid to prevent the building up of pressure necessary to hold spool 108 elevated and spool 110 depressed whereby fluid motor 102 will remain idle with valve 170 closed.

While a single form of the invention has been illustrated, it will be obvious that many minor changes may be made in the construction and relation of parts without departing from the spirit and scope of the invention as set forth in the following claims.

I claim:

1. Hydraulic apparatus comprising a source of fluid pressure; a fluid motor; valve mechanism for controlling the flow of pressure to said motor to effect the operation thereof; a rotatable work support, Geneva gearing for causing intermittent rotation of said work support; a fluid motor for driving said Geneva gearing, a second valve mechanism for controlling the operation of said second fluid motor, said second valve mechanism having a flow control spool for governing the flow of fluid pressure from said first-mentioned valve mechanism to the second fluid motor to regulate the rate of operation thereof, a second spool; and, means actuated by the driving gear of said Geneva

gearing for moving said second spool to render said flow control spool operative at different stages of operation of said work support and to redirect fluid from said first valve mechanism back to said first valve mechanism to initiate a cycle of operation of said first-mentioned fluid motor.

2. Hydraulic apparatus comprising a source of fluid pressure; a fluid motor; valve mechanism for controlling the flow of pressure to said motor to effect the operation thereof; a rotatable work support, Geneva gearing for causing intermittent rotation of said work support; a fluid motor for driving said Geneva gearing, a second valve mechanism for controlling the operation of said second fluid motor, said second valve mechanism having a spool valve; and, means actuated by the driving gear of said Geneva gearing for moving said spool valve to a position to redirect fluid from said first valve mechanism back to said first valve mechanism to initiate a cycle of operation of said first-mentioned fluid motor.

3. Hydraulic apparatus comprising a source of fluid pressure; a reversible fluid motor; mechanism for controlling the flow of pressure from said source to said motor to effect cyclical operation thereof, said mechanism having a valve element responsive to fluid pressure to move to a position to direct fluid to said motor to cause operation thereof in one direction; means for urging said valve element to a second position to cause said motor to operate in a reverse direction; a second fluid motor; means actuated by said first motor at the termination of operation in the reverse direction to direct fluid pressure from said source to said second fluid motor; a work supporting table intermittently rotated by said second fluid motor; means actuated by the second fluid motor for directing fluid pressure to said valve element to move the same to the first-mentioned position to initiate operation of said reversible motor in said one direction.

4. Hydraulic apparatus comprising a source of fluid pressure; a power unit having a reciprocable ram; a work holder intermittently movable relative to said ram; a fluid motor for driving said work holder; control mechanism for said power unit and fluid motor to cause sequential operation thereof, said mechanism having a flow-directing element operative to alternately direct fluid from said pressure source to said power unit and said work holder, said element being responsive to the application of fluid pressure thereto to direct pressure from said source to said power unit; and means actuated by said fluid motor for momentarily applying fluid pressure to said flow-directing element to initiate the operation of said power unit.

5. Hydraulic apparatus comprising a source of fluid pressure; a power unit having a reciprocable ram; a work holder intermittently movable relative to said ram to successively register stations thereon with said ram; a fluid motor for driving said work holder; control mechanism for said power unit and fluid motor to cause sequential operation thereof, said mechanism having a flow-directing element operative to alternately direct fluid from said pressure source to said power unit and said work holder, said element being responsive to the application of fluid pressure thereto to direct pressure from said source to said power unit; means actuated by said fluid motor for momentarily applying fluid pressure to said flow-directing element to initiate the operation of said power unit; means for restricting exhaust

flow from said power unit during the power stroke thereof to create back pressure; and means for applying such back pressure to said flow-directing element to continue the operation of said power unit after said fluid motor actuated means ceases to function.

6. In hydraulic apparatus a fluid circuit including a reservoir; a reversible fluid motor; pump means for drawing fluid from said reservoir and supplying the same under pressure to said motor; means for controlling the supply of fluid to said motor comprising pressure responsive valve mechanism; a work holder; fluid pressure operated means for intermittently moving said work holder relative to said fluid motor, said valve mechanism causing fluid from said pump means to flow from said valve means directly to said fluid pressure operated means when said fluid motor is idle; and means actuated by said fluid pressure operated means at a predetermined stage of movement of said work holder for redirecting fluid pressure back to said valve mechanism to initiate the operation of said fluid motor.

7. A hydraulic system having a source of fluid pressure; a reversible fluid motor; control mechanism between said pressure source and said motor, said mechanism providing for forward and reverse operation and idle periods of said motor; a movable work holder; means for intermittently moving said work holder relative to said fluid motor, said means having a second fluid motor and Geneva gearing; and means actuated by said Geneva gearing for changing the rate of operation of said second fluid motor at different stages of operation of said Geneva gearing, said control mechanism interrupting the flow of fluid to said second fluid motor and consequently the operation thereof during the operation of said first-mentioned fluid motor.

8. A hydraulic system having a source of fluid pressure; a reversible fluid motor; control mechanism between said pressure source and said motor, said mechanism providing for forward and reverse operation and idle periods of said motor; a movable work holder; means for intermittently moving said work holder relative to said fluid motor, said means having a second fluid motor and Geneva gearing; means operated by said second fluid motor at a predetermined stage of operation of said Geneva gearing for actuating said control mechanism to initiate the operation of said first-mentioned fluid motor; and means actuated by said Geneva gearing for changing the rate of operation of said second fluid motor at different stages of operation of said Geneva gearing, said control mechanism interrupting the flow of fluid to said second fluid motor and consequently the operation thereof during the operation of said first-mentioned fluid motor.

9. A hydraulic press having an index table comprising a source of fluid pressure; a power cylinder having a ram disposed for reciprocation toward and away from said table; means for imparting intermittent movement to said table said means having a fluid motor and Geneva gearing with star wheel and driver; control mechanism between said pressure source and power cylinder, said mechanism directing fluid pressure to said power cylinder to cause a pressing and return stroke of said ram, said mechanism directing fluid pressure to said fluid motor when said power cylinder is idle; additional control means for said fluid motor, said means providing for different rates of operation of said fluid motor during indexing and stationary periods of said table;

and means actuated by the driver of said Geneva gearing to cause said control mechanism to initiate a pressing stroke of said ram, the first-mentioned control mechanism interrupting fluid flow to said motor during the operation of said power cylinder.

10. In a hydraulic press having an index table, a source of fluid pressure; power cylinder means having a ram movable toward and away from said table; means for causing intermittent rotation of said table; control mechanism operative to regulate flow of fluid from said source to said power cylinder to cause cycles of operation including pressing and return strokes, said control mechanism also being operative to direct fluid to said table rotating means between cycles of operation of said power cylinder; and means for changing the rate of operation of said table rotating means when said table is stationary, 20 said control mechanism serving to stop the operation of said table rotating mechanism during the operation of said power cylinder.

11. A hydraulic index table comprising a support; a disk-like table journaled for rotation on said support; means for causing intermittent rotation of said table having a Geneva gear with a driver; a fluid motor connected with said driver; means for controlling the operation of said fluid motor, said last-named means having a flow-control mechanism responsive to a pressure differential; means for creating a pressure differential; means for applying said pressure differential to said flow-control mechanism; and means operated by said Geneva gear for rendering said last-named means ineffective.

12. A hydraulic index table comprising a support; a disk-like table journaled for rotation on said support; means for causing intermittent rotation of said table having a Geneva gear with a driver; a fluid motor connected with said driver; means for controlling the operation of said fluid motor, said last-named means having a flow-control mechanism responsive to a pressure differential; means for creating a pressure differential; means for applying said pressure differential to said flow-control mechanism to vary the operation of said fluid motor; and means operated by said Geneva gear for interrupting the operation of said pressure differential creating means.

13. A hydraulic index table comprising a support; a disk-like table journaled for rotation on said support; means for causing intermittent rotation of said table having a Geneva gear with a driver; a fluid motor connected with said driver; means for controlling the operation of said fluid motor, said last-named means having a flow-control mechanism responsive to a pressure differential; means for creating a pressure differential; means for applying said pressure differential to said flow-control mechanism to vary the operation of said fluid motor; means for changing the pressure differential; and means actuated by said Geneva gear for interrupting the operation of said pressure differential creating means.

14. A hydraulic circuit comprising a source of fluid pressure, a fluid motor; a rotatable carrier; Geneva gearing connecting said motor and carrier to cause intermittent rotation of the latter; control mechanism for said fluid motor having a spool valve between said source of fluid pressure and said fluid motor; means for creating and applying a pressure differential to said spool valve to govern the operation of said fluid motor; and

15

valve means responsive to the operation of said Geneva gearing and to fluid pressure to interrupt the operation of said pressure differential creating means and the operation of said fluid motor.

15. In a hydraulic circuit, a source of fluid pressure; a rotatable carrier; a fluid motor; Geneva gearing connecting said motor and carrier to cause intermittent rotation of the latter; control mechanism for said fluid motor having a flow-control device responsive to a pressure differential to govern the operation of said motor; means for creating and applying a pressure differential to said flow-control device; means operated by said Geneva gearing for interrupting the operation of said pressure differential creating means, said Geneva gearing operated means cooperating with said flow-control in response to the application of fluid pressure to interrupt the operation of said fluid motor; and means for controlling the application of fluid pressure to said cooperating means and flow-control.

16. In a hydraulic circuit, a source of fluid pressure; a fluid motor; means rotated by said motor; control means for said motor connected with said pressure source, said control means having a flow-control spool valve between said pressure source and said motor, said valve being responsive to differential pressures to vary the operation of said motor; means for creating and applying a pressure differential to said flow-control valve; a second spool valve in said control means, said second valve being operated by said first-mentioned means to interrupt the operation of said pressure differential creating means, said second valve cooperating with said flow-control in response to the application of fluid pressure to interrupt the operation of said fluid motor; an exhaust line leading from said motor control mechanism; and means in said line for applying fluid pressure to said cooperating valves.

17. A hydraulic system comprising a source of fluid pressure; a reversible fluid motor; control mechanism between said source and said motor; a second fluid motor; a second control mechanism; valve means in the first mentioned control mechanism responsive to fluid pressure to direct fluid from said source to said reversible motor to cause operation thereof in one direction; means responsive to a fluid pressure drop which is dependent upon operation of said motor in said one direction to continue such operation; means for actuating said valve means to cause reverse motor operation when operation in said one direction is discontinued; means actuated by said reversible fluid motor at the termination of reverse operation to direct fluid from said source to said second control mechanism to cause the operation of said second fluid motor; motor speed regulating valve means forming a part of the control mechanism for said second fluid motor; a flow directing element in said second control mechanism for rendering said speed control valve operative and inoperative; and means actuated by said second fluid motor for operating said last-mentioned element, said flow directing element also being effective when operated by said last-named means to redirect fluid from said source to the first-mentioned control mechanism to initiate fluid flow to said reversible fluid motor.

18. In a hydraulic system, a source of fluid pressure; a reversible fluid motor; control mechanism between said pressure source and said motor, said control mechanism having a reversing valve responsive to fluid pressure to cause operation of said fluid motor in one direction; a second fluid

16

motor; a second control mechanism; means actuated by said reversible fluid motor at the termination of reverse operation thereof to direct fluid from said source to said second control mechanism to effect the operation of said second motor; a member actuated by said second motor; speed control means in said second control mechanism; and means actuated by said member in certain stages of operation thereof for rendering said speed control means operative and inoperative, said means being operative at another stage of operation of said member to redirect fluid pressure to said first control mechanism to initiate a cycle of operation of said reversible fluid motor.

19. In a hydraulic system, a source of fluid pressure; a reversible fluid motor; control mechanism between said pressure source and said motor, said control mechanism having a reversing valve responsive to fluid pressure to cause operation of said fluid motor in one direction; a second fluid motor; a second control mechanism; means actuated by said reversible fluid motor at the termination of reverse operation thereof to direct fluid from said source to said second control mechanism to effect the operation of said second motor; a member actuated by said second motor; speed control means in said second control mechanism; and means actuated by said member in certain stages of operation thereof for rendering said speed control means operative and inoperative, said means being operative at another stage of operation of said member to redirect fluid pressure to said first control mechanism to initiate a cycle of operation of said reversible fluid motor; and means for selectively preventing the redirecting of fluid pressure to said first control mechanism when said member reaches the latter stage of operation.

20. In a hydraulic press, a source of fluid pressure; a power cylinder with a ram; control mechanism between said pressure source and said power cylinder, said mechanism having a reversing valve responsive to fluid pressure to cause the advancement of said ram; an index table disposed for intermittent rotation in registration with said ram; a fluid motor for driving said index table; said control mechanism directing fluid from said source to said fluid motor at the termination of a cycle of operation of said ram; means actuated by said fluid motor at a predetermined stage of operation of said index table for interrupting the flow of fluid to said fluid motor and directing fluid back to said control mechanism to initiate a cycle of operation of said ram; and means actuated by said index table for selectively preventing the directing of fluid back to said control mechanism when said means is actuated by said fluid motor.

21. In a hydraulic press, a source of fluid pressure; a power cylinder with a ram; control mechanism between said pressure source and said power cylinder, said mechanism having a reversing valve responsive to fluid pressure to cause the advancement of said ram; an index table disposed for intermittent rotation in registration with said ram; a fluid motor for driving said index table; said control mechanism directing fluid from said source to said fluid motor at the termination of a cycle of operation of said ram; means actuated by said fluid motor at a predetermined stage of operation of said index table for interrupting the flow of fluid to said fluid motor and directing fluid back to said control mechanism to initiate a cycle of operation of said ram; and a by-pass valve; and cam means on said index

table for actuating said by-pass valve to prevent the directing of fluid back to said control mechanism when said means is actuated by said fluid motor.

22. In a hydraulic press, a source of fluid pressure; a reversible fluid motor; control mechanism between said pressure source and said motor, said mechanism having a reversing valve responsive to fluid pressure to cause operation of said motor in one direction; an index table disposed for intermittent rotation relative to said reversible fluid motor; a fluid motor for driving said index table, said control mechanism directing fluid from said source to said second-mentioned fluid motor at the termination of a cycle of operation of said reversible fluid motor; means actuated by said second-mentioned fluid motor at a predetermined stage of operation of said index table for interrupting the flow of fluid to said second-mentioned fluid motor and directing fluid back to said control mechanism to initiate a cycle of operation of said reversible fluid motor; and means actuated by said index table for selectively preventing the directing of fluid back to said control mechanism and re-establishing the flow of fluid to said second-mentioned fluid motor after said means is actuated thereby.

23. The combination with an index table and a mechanism for performing operations upon bodies supported on said index table, of a vari-

30

able speed motor; a Geneva drive between said motor and said index table, said Geneva drive serving to cause intermittent movement of said index table, said mechanism performing said operations during idle periods of said index table; means actuated by the Geneva driving mechanism during the idle periods of said index table to change the speed of said motor; and means controlled in part by said Geneva driving mechanism and in part by said operation performing mechanism for interrupting the operation of said motor during a portion of each idle period of said index table.

CECIL E. ADAMS.
